UNITED STATES PATENT OFFICE.

ABE GOLUB, OF ST. LOUIS, MISSOURI.

RUBBER HEEL.

Application filed December 21, 1925. Serial No. 76,618.

My invention relates to improvements in rubber heels, and has for its primary object a rubber heel which is so constructed as to practically eliminate the possibility of slipping.

A further object is to construct a rubber heel which is provided with intersecting channels and have that portion of the heel underneath the channels more resilient than the remainder of the heel so that when the heel is stepped on the channels will close or have their edges moved toward each other and the heel concave thereby setting up a suction underneath the heel and preventing same from slipping.

In the drawings:

Fig. 1 is a bottom plan view of my improved heel;

Fig. 2 is a top plan view of the same;

Fig. 3 is an edge view;

Fig. 4 is a cross section taken on the line 4—4 of Fig. 2;

Fig. 5 is a bottom plan view of my heel illustrating the manner in which the channels close when pressure is placed on the heel; and

Fig. 6 is an enlarged section taken on the line 6—6 of Fig. 1 illustrating more clearly the shape of the channel.

In the construction of my device I employ a heel 7. This heel is preferably composed of live rubber. The heel is provided with a bottom face 8 and a top face 9. Formed in the face 8 and spaced apart from the outer edge of the heel are a plurality of openings 10. These openings extend only partially through the heel and are for the purpose of receiving the securing means, such as nails or the like, by means of which the heel is fastened to a shoe. The openings 10 are each preferably surrounded by a circular rib or ring 11. Formed in the bottom 8 are intersecting channels 12. These channels have their edges undercut as illustrated by the numeral 13 so as to leave a sharp edge 14 at the face 8. Adjacent the point of intersection are buttons or projections 15, the purpose of which will be ex-

plained in detail later. Formed in the face 9 and directly opposite the channels 12 is a recess 16 leaving a relatively thin wall 17 between the bottom of the channel and the recess. After the rings 11 become worn off from walking this thin wall together with the projections or buttons 15 permits the channels to close when the heel is stepped on by reason of the fact that the buttons 15 push upward and bend the wall 17 so that the channels when the heel is stepped on assume the position shown in Fig. 5. This will naturally concave that portion of the face 8 adjacent the buttons and have a tendency to create a suction causing the heel to firmly grip and preventing slipping when the ribs 11 are worn off, and on account of the thinness of the wall 17 no uncomfortable feeling will result from the buttons 15.

While I have shown two channels intersecting each other at right angles, still it is obvious that the angle of intersection can be varied as desired, and that the number of intersecting channels may be increased without departing from the spirit of my invention.

I may, also, if desired, omit the circular ribs or rings 11 and also the buttons 15 without departing from the spirit of my invention. The recess 16 may also be made cylindrical, that is of equal depth throughout without departing from the spirit of my invention.

Having fully described my invention, what I claim is:—

A rubber heel comprising a resilient member having a recessed upper face and a lower face, and a plurality of intersecting channels having undercut edges formed in the lower face of said member, said channels located directly below the recess in the upper face whereby that portion of the heel at the recesses is rendered more flexible, and the lower face of the member along said channels more resilient.

In testimony whereof I have affixed my signature.

ABE GOLUB.
